BOTTLE-WASHING MACHINE.

1,288,737.

Specification of Letters Patent. Patented Dec. 24, 1918.

Application filed July 22, 1918. Serial No. 245,980.

To all whom it may concern:

Be it known that I, WADE L. STREET, a citizen of the United States, and a resident of the city of Chicago, county of Cook, and State of Illinois, have invented certain new and useful Improvements in Bottle-Washing Machines, of which the following is a full, clear, and exact description, reference being had to the accompanying drawings, forming part of this specification.

This invention relates to bottle washers and its principal object is to provide a machine, automatic in operation, for washing the outsides of bottles after they have been filled. The machine has been designed especially for washing filled catchup bottles, but it is not intended to limit its use for this purpose, as it may be used for washing any kind of bottles. It is well known that after bottles or jars are filled with catchup, mustard or the like, and have been corked, the outer faces of the bottles or jars are smeared more or less with the material. This must be removed before the labels are applied, and usually workmen and women are employed to wash the bottles. The present machine has been designed to automatically wash the outsides of the bottles, and deliver them in clean condition preparatory to labeling them. The invention consists in the several novel features hereinafter set forth and claimed.

The invention is clearly illustrated in the accompanying drawings, in which:

Figure 1 is a plan of a bottle washer embodying a simple form of the present invention; Fig. 2 is a side elevation thereof; Fig. 3 is an enlarged vertical cross section taken on the line 3—3 of Fig. 2; Fig. 4 is an enlarged vertical cross section taken on the line 4—4 of Fig. 2; Fig. 5 is an enlarged vertical longitudinal section taken on the line 5—5 of Fig. 1 and Fig. 6 is a fragmental plan of a bottle conveyer and a water spraying pipe used in the machine.

Referring to said drawings, in the embodiment of the invention illustrated therein, 10, designates a frame of strong and substantial construction for supporting the operative portions of the machine. Said frame is composed of uprights 11, connected by longitudinally extending bars 12, 12^a, and transversely extending bars 13, 13^a. Said bars may comprise angle iron bars, or

other structural iron bars bolted or otherwise secured together.

Extending lengthwise of the frame is a bottle conveyer 14, which may comprise one or more link belts or chains 15, and conveyer fingers 20 secured thereto. The chains 15 are trained around sprocket wheels 16, mounted on shafts 17, 18, journaled in bearing boxes 19, secured to the end uprights 11. Certain of the links of the chains 15 have transversely extending lugs, and the fingers 20 are riveted or otherwise secured to the lugs of both chains. Conveniently the chains may run on horizontal, lengthwise extending tracks or supports such as boards 21, 22, secured upon the transverse frame bars 13. Along the upper portion of the conveyer, underneath the protruding ends of the fingers 20, is a table or platform 23, which may comprise a number of spaced slats which support the bottles as they are conveyed past the scrubbing or washing apparatus. A supporting strip 24 underlies the protruding ends of the fingers of the lower portion of the conveyer. In the particular form shown, crosswise extending track and platform supporting bars 25 support the conveyer tracks and platform above the cross bars (see Fig. 3). The fingers 20 have upright webs or flanges 26, which are adapted to engage the sides of the bottles (B) and propel them along the platform 23.

The main drive shaft is seen at 36 and is journaled in bearing boxes 66, secured to cross-bars 13^a of the frame. Tight and loose pulleys, 67, 68, are mounted on the drive shaft and may be belted to any suitable source of power. The conveyer shaft 17 is driven from the main shaft by speed reducing gearing here shown to comprise a bevel pinion 69 on the drive shaft 36, a bevel gear 70 mounted on a counter-shaft 71 and meshing with the pinion 69, a small sprocket wheel 72 on the counter-shaft 71, a large sprocket wheel 73 mounted on the conveyer shaft 17 and a sprocket chain 74 trained around said sprocket wheels 72, 73.

Adjacent the end A, of the frame (which is the receiving end of the machine) are the bottom scrubbing brushes 27. Said brushes 27 are round and are mounted on horizontal shafts 28, which are journaled in bearing boxes 29, secured on two of the lengthwise extending frame members 12. Intermesh-

ing gear wheels 30, are mounted on the brush shafts 28, and all of said shafts are driven by a sprocket wheel 31 which is fast upon one of said shafts. Adjacent the 5 brushes is a counter shaft 32 which is journaled in bearing boxes 33 secured to two lengthwise extending frame members 12^a, and fast to said counter shaft 32 is a sprocket wheel 34 which is connected to and 10 drives the sprocket wheel 31 by a sprocket chain 35. The counter shaft 32 is driven from the main drive shaft 36 by miter pinions 37, 38, fast upon the respective ends of the counter shaft 32 and main drive shaft 36. 15 A guide bar 39 for holding the bottoms of the bottles against the brushes 27 extends lengthwise of the machine directly above the conveyer 14 and is supported by brackets 40 which are secured to the frame bars 13. 20 The front end of said guide bar 39 is curved forward to facilitate the entrance of the bottles between the bar and brushes. A guide bar 76 is supported in line with the front faces of the brushes 27 and serves as 25 a guide in laying the bottles upon the platform between the conveyer fingers. Immediately above the path of travel of the bottles is a bottle retaining member 41 which is supported from the frame members 30 13 by hinged supports 42. Said bottle retaining member prevents the bottles from being dislodged from the conveyer by the action of the brushes 27. A water trough 43 is secured to the frame and extends under- 35 neath the brushes 27 and catches the water and material washed off the bottoms of the bottles. A discharge pipe 46 conducts the water and material away from the trough. The rear wall 44 of the trough extends up 40 behind the brushes 27, and a cover 45 above the brushes 27 prevents water from being sprayed out of the machine by the revolving brushes 27.

Beyond the bottom washing brushes is the 45 side scrubbing or washing device which is in the form of an endless band, and comprises a plurality of connected brushes 47, which are located above the path of travel of the bottles and act to wash the sides of 50 the bottles. In the form shown in the drawings, said brushes 47 extend lengthwise of the machine and are mounted on two endless link belt chains 48 which are trained around sprocket wheels 49, 50, fast on shafts 51, 52, 55 that are journaled in bearing boxes 53 secured on the frame members 13^a. The brushes 47 are driven in the direction of the arrow in Fig. 4, and their path of movement along the bottles is on a slight incline to 60 follow generally the outline formed by the neck and body of the bottles. The shaft 52 is the driving shaft for the brushes 47 and is driven from the main drive shaft 36 by sprocket wheels 54, 55, fast on the shafts 65 36, 52, respectively, and a sprocket chain 56

trained around said sprocket wheels 54, 55. A bottle retaining bar 78 secured to the frame of the machine by brackets 79 lies underneath the brushes 47 at the rear edge of the platform and prevents the bottles 70 from being swept off the platform by the action of the brushes 47. A casing or housing 57, secured to the frame 10, covers the brushes 47 and acts to prevent water from being sprayed outside of the machine. A drip pan 58, carried by the frame of the machine beneath the upper portion of the conveyer 15, catches the water and material washed off the bottles by the brushes 47, and a discharge pipe 59 leads from the drip pan 80 and conveys the water and material away. 85 Hot water is supplied to the brushes and bottles by spray pipes 60, 61, which lead from a main supply pipe 62. A water supply pipe 63 and steam supply pipe 64 open to the main supply pipe 62, whereby hot water may be supplied to the spray pipes. The pipe 60, leads along the top and front of the brushes 27, and its lower side is perforated. The hot water is directed through 90 said perforations to the bristles of the brushes 27, and to the bottles, as seen in Fig. 3. The pipe 61 leads along the forward side of the brushes 47 and is perforated along its rear side, whereby hot water 95 is sprayed upon the bristles of the brushes 47 and to the sides of the bottles. Said pipe 61 has a branch 65 which leads along one end of the brushes 47 and is perforated along its bottom. At this place the bottles 100 are rinsed after having been scrubbed on their bottoms and sides.

In the operation of the machine, the conveyer 14 travels in the direction of the arrow *a* (Figs. 2 and 5). The hot water having been turned on, the bottles B are laid on the receiving end of the platform 23, between the conveyer fingers 20, the bottoms of the bottles being placed against the guide 76. 105 The conveyer fingers 20 propel the bottles 110 past the brushes and, while being propelled, they roll along the platform, thereby exposing every part of their sides to the action of the brushes. When they reach the rotating bottom washing brushes 27, their bottoms 115 are held against the bristles of the rotating brushes by the guide bar 39. By reason of the fact that two of said brushes rotate in one direction and the other two rotate in the opposite direction, a very thorough scrubbing of the bottoms is obtained. 120

After passing the bottom washing brushes, the bottles are conveyed past the side washing brushes 47. The speed of travel of the bottles is much less than the speed of travel of the brushes 47. Consequently, the general direction of travel of the bristles of the brushes 47 will be lengthwise of the bottles. Inasmuch as the bottles are rolled along the platform 23 by the conveyer, and inasmuch 125 130

as the brushes 47 are long enough to cover ten or twelve bottles at a time, each bottle will be acted on for some considerable time and each part of its side will be exposed to 5 the action of the brushes, whereby they are thoroughly cleaned.

After passing the brushes 47 the bottles pass the rinsing pipe 65 where clear water is sprayed upon them. A receiving table 10 (not shown) may be placed at the discharge end C upon which the clean bottles are delivered by the conveyer chain 14.

More or less variation of the exact details of construction is possible without departing 15 from the spirit of this invention. I desire, therefore, not to limit myself to the exact form of construction shown and described, but intend, in the following claims, to point out all of the invention disclosed herein.

20 I claim as new, and desire to secure by Letters Patent:

1. In a bottle washing machine, a platform, a bottle conveyer for rolling bottles along said platform, rotating bottom scrubbing brushes, traveling side scrubbing brushes moving substantially lengthwise of the bottles, and driving mechanism for said conveyer and brushes.

2. In a bottle washing machine, a platform, an endless conveyer for rolling bottles along said platform, rotating bottom scrubbing brushes adjacent the path of travel of the bottles, an endless traveling side scrubbing brush moving through the path of 30 movement of the bottles in a direction lengthwise of the bottles, and driving mechanism for said conveyer and brushes.

3. In a bottle washing machine, a platform, an endless conveyer for rolling bottles along said platform, rotating bottom scrubbing brushes adjacent the path of movement 40 of said bottles, the adjacent brushes rotat-

ing in opposite directions, an endless traveling side scrubbing brush, moving through the path of movement of the bottles in a direction lengthwise of the bottles, guides for the bottles and driving mechanism for the conveyer and scrubbing brushes.

4. In a bottle washing machine, a platform, an endless conveyer chain having bottle propelling fingers projecting from one side thereof, supports for said chain, rotating bottom scrubbing brushes adjacent the path of movement of the bottles, an endless traveling side scrubbing brush moving 50 through the path of movement of the bottles in a direction lengthwise of the bottles, a guide bar for preventing lengthwise movement of the bottles under said side scrubbing brushes, a main drive shaft and gearing between said drive shaft and conveyer and brushes.

5. In a bottle washing machine, a platform, a conveyer for rolling bottles along said platform, rotating bottom scrubbing 65 brushes, means for holding the bottles against said brushes, an endless traveling side scrubbing brush moving through the path of movement of the bottles in a direction lengthwise of the bottles, bottle retaining means under said brush for holding the bottles on the table against the action of said brush, driving mechanism for said conveyer and brushes, and water spraying pipes located adjacent said brushes.

6. In a bottle washing machine, a platform, a bottle conveyer for rolling bottles along said platform, rotating bottom scrubbing brushes, traveling side scrubbing brushes moving substantially lengthwise of 80 the bottles, and driving mechanism for said conveyer and brushes, and water spraying pipes located adjacent said brushes.
